CLAIM

The ornamental design for a golf putting guide, substantially as shown and described.

DESCRIPTION

FIG. 1 is a top perspective view of the new ornamental design.
FIG. 2 is a front view of the design.

FIG. 3 is a right side view of the design.

FIG. 4 is a left side view of the design.

FIG. 5 is a top view of the design; and,

FIG. 6 is a bottom view of the design.

Those features shown in broken lines represent environmental structure and form no part of the claimed design.
